SMOKING PIPE, CIGAR, OR CIGARETTE HOLDER

Roy Brigham, Toronto, Ontario, Canada

Application February 24, 1938, Serial No. 192,341
In Canada April 30, 1937

5 Claims. (CL 131—204)

This invention relates to an improved type of a stem for smoking pipe, cigarette holder and the like and has for its object removing from the tobacco smoke, the tars, volatile oils, and other moisture and disposing of them in such a manner as to substantially prevent their being carried into the mouth of the smoker and, at the same time, prevent the pipe, cigar or cigarette holder from becoming rancid.

For an understanding of this invention and the manner in which the above mentioned objects are obtained, reference is to be had to the following description, illustrated by the accompanying drawing in which:

Figure 1 is a cross sectional view of a pipe embodying the subject matter of this invention;

Figure 2 shows a cross section of the improved pipe with stem detached;

Figure 3 shows a cross sectional view of the mouthpiece of the pipe with the porous smoke duct removed; and

Figure 4 shows a cross sectional view of the porous smoke duct.

Like characters of reference refer to like parts throughout the specification and drawing.

The pipe illustrated in the drawing comprises a bowl 10 having a shank 11 extending outwardly therefrom and preferably from the base thereof. The mouthpiece 12 is connected to the shank 11 in the usual manner.

The passageway or smoke duct 13 is formed in the mouthpiece 12 and is widened as indicated at 14 to receive the non-porous tube 15. The non-porous tube 15 is preferably fabricated from metal, such as aluminum or an alloy thereof, and extends into the shank 11 approximately to the bowl 10 of the pipe.

The inner surface of the shank 11 is cut away as indicated to form a closed air chamber 16 between the tube 15 and the inner surface of the shank 11. The air chamber 16 serves a dual purpose inasmuch as it tends to ease the passage of the tube 15 into the shank 11 when attaching the mouthpiece thereto and when the shank 11 is in place tends to keep the outer surface of the tube 15 cool.

The tube 15 makes a snug and substantially air-tight fit with the shank 11 approximate to the bowl while the other end makes a substantially air-tight fit in the bore of the mouthpiece 12.

The porous tube 17, formed for example of light wood which has been cured to open the pores, is removably entered into the non-porous tube 15. One end of the porous tube 17 is provided with a nipple 18. The nipple 18 is preferably of metal

and tapered to engage with the inner surface of the forward end of the tube 15 and in substantially air-tight engagement therewith. The porous tube 17 is substantially the same length as the non-porous tube 15 and terminates at the mouthpiece end of the tube 15 making a substantially air-tight fit with the mouthpiece 12. The non-porous tube 17 forms a continuation of the passageway 13 and provides a smoke duct between the bowl 10 of the pipe and the passageway 13 formed in the mouthpiece 12.

When the various parts of the pipe are assembled, the air chamber 16 is formed between the outer surface of the porous tube 17 and the inner surface of the non-porous tube 15. The air chamber 16 forms an essential part of my invention.

I have found my invention in operation removes the tars, volatile oils and moisture from the smoke during its passage through the porous tube 17. The tars collect on the inside surface of the porous tube, the volatile oils are absorbed into the pores thereof while the moisture passes through the pores into the air chamber 16 from which it may be readily removed periodically by separating the mouthpiece 12 from the shank 11, taking the porous tube 17 out of the non-porous tube 15 and giving the mouthpiece a slight shake. The tars are easily removed from the interior of the porous tube 17 by passing a pipe cleaner through. On exposure to the air for a few minutes, the volatile oils evaporate as does the remainder of the moisture, and the tube is again ready for use.

I have found also that pipes, and the like, embodying my invention do not become rancid or sour as is common in pipes where no provision is made to prevent the fermentation of the volatile oils and tars. In addition, it is not necessary to provide filters or any other obstructions in the smoke duct to impede the passage of those impurities to the mouthpiece.

Having thus fully described my invention, what I claim as new and desire to secure by Letters Patent is:

1. A stem for pipes, cigarette holders and the like, comprising a smoke duct, a non-porous tube entered in said duct, and spaced from the wall thereof to form a closed chamber therebetween, and a porous tube removably fitted into said non-porous tube and spaced therefrom to form a closed chamber.

2. A pipe of the class described comprising a bowl and stem, a smoke duct through said stem and having an enlarged portion, a non-porous tube bridging said enlarged portion forming a

- closed chamber between the inner wall of the enlarged portion of the duct and the outer wall of said tube, and a removable porous tube fitted into the non-porous tube and spaced therefrom to form an air chamber between the inner wall of the non-porous tube and the outer wall of the porous tube.
3. A pipe of the class described, comprising a bowl and a stem, a smoke duct through said stem and having an enlarged portion, a non-porous tube bridging said enlarged portion forming a closed chamber between the inner wall of the enlarged portion of the duct and the outer wall of said tube, and a removable porous tube smaller than the non-porous tube fitting into said non-porous tube and spaced therefrom by a metal nipple attached to one end of the porous tube, thus forming a closed chamber between the inner wall of the non-porous tube and the outer wall of the porous tube.
4. A pipe of the class described, comprising a bowl, a stem, and a mouthpiece, a smoke duct through said stem and having an enlarged portion, a non-porous tube attached to the mouthpiece, said tube bridging said enlarged portion of

the smoke duct and forming a chamber between the inner wall of the enlarged portion of the duct and the outer wall of said tube, and a removable dried wooden tube of smaller diameter fitting into said non-porous tube and spaced therefrom by a tapered nipple attached to one end of the dried wooden tube, said tapered nipple engaging the inner portion of the non-porous tube which bridges the enlarged portion of the smoke duct, to form a closed chamber between the non-porous tube and the removable wooden tube.

5. A pipe of the class described, comprising a bowl, a stem, and a mouthpiece, a smoke duct through said mouthpiece and stem leading to the bottom of the bowl, the smoke duct through the entire stem being of larger diameter than the rest of the smoke duct, a metal tube attached to the mouthpiece and extending therefrom to the bottom of the bowl, and a removable dried wooden tube within the metal tube and positioned therein out of contact with the walls thereof by a metal nipple, said wooden tube being removable from the stem with the metal tube and the mouthpiece.

ROY BRIGHAM. 25
